UNITED STATES PATENT OFFICE.

CARL BRAUER, OF HOSTOMITZ, NEAR TEPLITZ, AUSTRIA.

APPARATUS FOR TRANSFERRING BOTTLES OR THE LIKE TO AN ANNEALING-OVEN.

1,226,633.

Specification of Letters Patent. Patented May 22, 1917.

Application filed April 17, 1914. Serial No. 832,436.

To all whom it may concern:

Be it known that I, CARL BRAUER, working manager, a subject of the Emperor of Austria, and resident of Hostomitz, near 5 Teplitz, Bohemia, Empire of Austria, have invented a new and useful Improvement in or Relating to Apparatus for Transferring Bottles or the like to an Annealing-Oven, of which the following is a specification.

10 This invention relates to apparatus for transferring bottles or the like hereinafter referred to as bottles, to an annealing oven.

Automatic transferring apparatus are known which take the bottles direct from 15 the blowing machine, for example an Owens machine, forward them to the annealing oven and set them in transverse rows on the movable sole or floor thereof.

In such an apparatus according to the 20 present invention the principal novelty consists in the fact that the bottles which travel bottom first through a chute, pass downward and are received in an upright position in a receiver located in the entrance to 25 the annealing oven provided with a movable floor or sole, and are pushed forward out of the receiver on or on to the floor or sole by a pusher device, the chute, the pusher device and the receiver, being carried by a 30 carrier frame so reciprocated transversely to the direction of travel of the movable sole, that each bottle pushed or fed on to the latter comes beside the preceding one.

The general arrangement of the devices, 35 which can be erected at any time while the plant is in full operation, without interruption of working and without rearrangement of the Owens or like installation, is illustrated by way of example in Figure 1.

40 Fig. 2 is a view on a larger scale, partly in elevation and partly in section on A—B, Fig. 1, Fig. 2^a a perspective view of a detail of a device for inverting the bottles to be transferred one after another, and Fig. 3 is 45 a view partly in elevation and partly a section on C—D, Fig. 1. Fig. 4 illustrates in plan the driving apparatus for imparting the lateral motion to the two devices for feeding and placing the bottles in position 50 on the movable sole, these two devices being arranged side by side. Fig. 5 is an elevation of this apparatus seen from the right of Fig. 4. Fig. 6 represents in elevation the arrangement of levers and operating arms 55 for actuating the bottle placing devices, the

open and closed positions of which are shown diagrammatically in plan, Fig. 7.

As seen in Fig. 2, the adjustable bottle raising or ejecting plunger 1 is mounted under the bottle disk or table *c* of the Owens 60 or such like machine, in such manner that in its rise it pushes the bottle out of the cup or seat 2 of the disk and into the bottle inverter or tilter *d* mounted free above same. The bottle inverter *d* consists of a sleeve-like 65 or tubular member slotted or open at the top as shown in Fig. 2^a, and fixed to the frame of the bucket elevator *e*, Fig. 2. The device *d* is formed with a deflecting face 3 and a turning face 4 so inclined and opening 70 freely downward at the end, that the bottle ejected by the plunger 1 is tilted over by the faces 3 and 4 and delivered bottom downward on to a bucket 5 of the elevator *e* which carries it up. The driving mechanism 75 of the ejector plunger and of the elevator are in positive connection with each other, so that each bottle ejected and inverted is delivered with certainty to a bucket 5 of the elevator *e*. The bottle tilter *d* is preferably 80 so arranged that it can be swung aside or upward if required; it may also be provided with a pendulous flap for controlling the passage for the bottle through it. The bottles raised by the buckets 5 are delivered suc- 85 cessively to the known bottle depositing device *f* as each bucket reaches the reversing point of the elevator, as shown in Fig. 2. The bottle is deposited by the device *f* on to likewise known automatically discharging 90 cartridges *h* running on a conveyer track *g*, leading to the annealing oven, and is delivered to known catchers *i*, as shown by Fig. 3, from which it passes into the chute *k* and is delivered upright into the bottle placing 95 device *m* located over the conveyer band *l* of the annealing oven. In the constructional example illustrated, two bottle placing devices *m*, two chutes *k* and two pairs of catchers *i* are arranged side by side. The bottle 100 placing device *m* consists as shown in Figs. 3, 4 and 7, of a funnel-like receiver made in halves 6. The halves 6 are fixed at the free ends of the legs of a scissors motion 9, pivoted at 7 and opened and closed from the 105 point 8, Figs. 3 and 7, and below the scissors motion 9 is a pusher rod 13 mounted in the guide 10 and supported on rollers 11, 12, running on the conveyer-band *l*. From the pusher rod 13 rises an angularly bent 110

arm 14, Fig. 3, the upward portion of which carries the point of application 8 of the force for operating the scissors motion 9. The long horizontal portion of the arm 14 is 5 mounted to slide in eyes 15 fixed to an angularly bent lever 16. The bent lever 16 is mounted to swing laterally right and left about a pivot 18 on an arm 17 of the pillar supporting the rails of the conveyer track *g* 10 (Fig. 4) and to the short arm of the bent lever 16 is connected the chute *k* the lower end of which is carried by the support or guide 10. To the bent lever 16 is pivotally connected a nut 19, and the two nuts 19 used 15 in the case where two of the devices are disposed side by side, are mounted on a screw spindle 20 (see Figs. 4 and 5) fitted with one fast and two loose pulleys for an open and a crossed belt which pass at the 20 other end over a belt pulley on a counter shaft 21. The counter shaft 21 is adapted to be driven for example with three speeds, from the staff-wheel *n* that drives the band or rope of the conveyer track *g* to be referred 25 to hereinafter. To one of the nuts 19 is fixed a tappet 22 in the path of which is a weighted lever 23 connected to the belt shift fork, so that when the nuts reach either end position the weighted lever 23 is moved so 30 as by its weight to effect automatic shifting of the belts and thus reverse the motion of the nuts and of the entire bottle placing apparatus.

To the end of the pusher rod 13 extending 35 inward at the bottom from the bent arm 14 is connected a link 24 the other end of which is connected to the shorter arm of a powerful bell crank lever 25, Fig. 7. Bell crank lever 25 is pivoted at 26 on a support 27 40 carried by the arm 17'. To the long arm of each bell crank lever 25 is connected a link 28 and each of these links is connected to an operating lever 29, Figs. 3 and 6. Each of the levers 29 is pivotally mounted at 31 45 on a carrier 30 fixed to the rail supporting pillar, and its upper end extends into the path of the bottle carriages. To the carrier 30 are also pivoted at 32 the operating levers 33 the upper ends of which extend 50 into the path of the bottle carriages in a different plane than that of the operating levers 29, and each of the levers 33 is connected by a reversing link 34 to the adjacent lever 29 in such manner that when a lever 55 33 is moved to the right, the lever 29 connected to it by the reversing link 34 is swung to the left, while when the lever 29 is moved back to the right, the lever 33 coupled to it is swung back to the left. The separate 60 actuation of the levers 29 and 33 by the bottle carriages in such manner that at one time the lever 33 is moved and at the next the lever 29 is attained by making the striker or tripping arms of the successive bottle carriages of suitably different shape.

On the bottle carriage in Fig. 2, the striker or tripping arm *o* is of such shape that it throws over the levers 33, while the striker arm *p* on the bottle carriage in Fig. 3 can only actuate the levers 29.

Assuming now that a charged bottle carriage having a striker arm *o*, Fig. 2, in traveling in the direction of the arrow, Fig. 6, comes against the left hand lever 33, the striker arm *o* in the travel of the carriage 70 will move this lever over to the right, and the lever 29 coupled thereto will therefore be moved to the left, with the result that the pusher rod 13 of the left hand bottle placing device *m*, Fig. 7, which is in the advanced position will be retracted and the appertaining bottle receiver 6 will be closed. At the same time a bottle discharged from the bottle carriage through the pairs of catchers *i* and through the chute *k* is fed 75 into the bottle receiver 6 and set erect on the conveyer band *l*. When the striker arm *o* in the further travel of the bottle carriage comes against the second lever 33, this is moved over to the right and the lever 29 80 coupled to it is moved to the left, whereby the receiver 6 of the right hand bottle placing device *m* is opened, and the bottle which was received and set erect therein at the previous feed is pushed forward on the band *l* by the pusher rod 13. Thus both levers 29 have now been moved over to the 85 left and are in advance of the levers 33. Now when another charged carriage having a striker arm *p*, Fig. 3, in traveling in the 90 direction of the arrow Fig. 6, strikes the left hand lever 29, it will move this to the right and the lever 33 coupled thereto to the left, thus opening the receiver 6 of the left hand bottle placing device. At the same 95 time the appertaining pusher rod 13 pushes the bottle which was contained in this receiver, forward on the band *l* to a position beside the bottle previously pushed forward. When the arm *p* of the carriage strikes the 100 second lever 29, this lever is moved over to the right and the lever 33 coupled thereto to the left. The pusher rod of the right hand bottle placing device *m* is thus 105 retracted and the corresponding receiver or 110 funnel 6 closed, and at the same time a bottle is fed to this receiver from the bottle carriage. The placing of the bottles side by side is attained owing to the fact that during the operation of the bottle placing device the screw spindle 20 is rotated from the staff-wheel *n* of the bottle carriage driving mechanism and thereby such a travel is imparted to the nuts 19 that each chute *k* with its bottle receiver 6, scissors motion 9 115 and pusher rod 13 is caused to swing laterally on the pivots 18, and consequently the bottle to be pushed forward is placed beside that previously pushed forward. In 120 this way the bottles are always placed en- 125 130

tirely automatically in a row, on the conveyer band 1 of the annealing oven, as shown by Fig. 4, and the band is then moved forward automatically a sufficient distance to 5 allow the next row to be placed. The drive of the screw spindle 20 has then been so reversed by the weighted lever 23 that the bottle placing devices are moved in the opposite direction until the next row of bottles has 10 been placed by them.

The bottle conveying device described above is so constructed or arranged that bottles or the like of different sizes can with equal reliability be automatically placed in 15 rows in the annealing oven.

The device or apparatus hereinbefore described as arranged for power operation can of course be arranged for hand operation.

20 What I claim is:

1. Automatic bottle transferring apparatus including an endless conveyer for receiving the bottles direct from the machine, an annealing oven provided with a movable 25 sole, means for sliding the bottles bottom first including a chute, an open topped receiver in proximity to the annealing oven and adapted to receive the bottles from the chute erect, a pusher device for removing 30 the bottles from the receiver to said movable sole, and a reciprocating frame forming a support for the chute, the receiver and the pusher device, the said frame being

arranged transversely to the movement of the said sole for assembling the bottles in 35 juxtaposition and the said receiver being mounted to rock about a fixed point of the carrier frame and thereby have its open top closed during the backward motion of the carrier frame.

2. Automatic bottle transferring apparatus including an endless conveyer for receiving the bottles direct from the machine, an annealing oven provided with a movable sole, means for sliding the bottles bottom 40 first including a chute, an open-topped receiver in proximity to the annealing oven and adapted to receive the bottles from the chute erect, means for opening and closing the receiver, a pusher device for removing 45 the bottles from the receiver to said movable sole, and lever arms projecting into the path of the endless conveyer and arranged to move the pusher device and the receiver opening and closing means at intervals corresponding to the arrival of successive bottles. 50

In testimony, that I claim the foregoing as my invention I have signed my name in presence of two witnesses, this 2 day of 60 April, 1914.
